CLAIM

The ornamental design for a bottle lid, as shown and described.

DESCRIPTION

FIG. 1 is a top perspective view of a bottle lid, showing our design.

FIG. 2 is a front elevation view thereof.

FIG. 3 is a rear elevation view thereof.

FIG. 4 is a left side elevation thereof.

FIG. 5 is a right side elevation thereof.

FIG. 6 is a top plan view thereof.

FIG. 7 is a bottom plan view thereof; and,

FIG. 8 is a perspective view of the bottle lid of FIG. 1 wherein a nozzle of the bottle lid is open.

The broken lines in the drawings depict portions of the bottle lid that form no part of the claimed design.
